(57) **CLAIM**

The ornamental design for the automobile and toy replica thereof, as shown and described.

DESCRIPTION

FIG. 1 is a front, perspective view of an automobile and toy replica thereof showing our new design;

FIG. 2 is a rear perspective view thereof;

FIG. 3 is a front view thereof;

FIG. 4 is a rear view thereof;

FIG. 5 is a top plan thereof; and,

FIG. 6 is a right side view thereof, the left side view being a mirror image thereof with the exception of the fuel door which is not present on the left side.

The bottom view of the automobile and toy replica thereof forms no part of the claimed design.
